[57] CLAIM

The ornamental design for a flutist's lyre, as shown and described.

DESCRIPTION

FIG. 1 is a front, top and right side perspective view of a flutist's lyre showing my new design;

FIG. 2 is a rear elevational view;

FIG. 3 is a front elevational view; and

FIG. 4 is a left side elevational view, the right side elevational view being a mirror image thereof.
